UNITED STATES PATENT OFFICE.

WALTER D. BUTZ, OF NORRISTOWN, PENNSYLVANIA.

DESIGN FOR A STOCKING.

Application filed September 6, 1922. Serial No. 3,636. Term of patent 14 years.

To all whom it may concern:

Be it known that I, WALTER D. BUTZ, a citizen of the United States, residing in Norristown, Pennsylvania, have invented a new, original, and ornamental Design for a Stocking, of which the following is a specification, reference being had to the accompanying drawing, forming part thereof, in which the figure is a side view of the stocking.

I claim:

The ornamental design for a stocking, as shown.
